1

This invention relates to electron discharge devices employing hollow resonators constructed for use as generators of oscillations. The invention is concerned with such devices of the kind in which reflecting means are provided capable, if suitably charged, of setting up a reflecting field to cause the electrons in the electron beam of the device after having passed through the gap in the resonator where they become velocity modulated to be reflected back through the gap. The resonator in such devices may be of toroidal form and is tuned in known manner to the frequency of the oscillations that it is desired to generate.

It is necessary for efficient operation that the electric field which is set up in operation between the resonator and the reflecting electrode should firstly be such as to cause a reasonable degree of bunching. Secondly, the field should be such as to ensure that as much as possible of the electron beam is reflected back through the gap and thirdly the field should be such that the drift time of the axial and marginal electrons is substantially the same so that substantially all such electrons after reflection reach the gap in phase.

It has been proposed in known forms of devices of the kind referred to, to employ a reflecting electrode in the form of a flat disc or in the form of a portion of a sphere with the concavity facing the resonator. In the former case the electric field which is set up between the resonator and the reflecting electrode is composed of equipotential surfaces which, adjacent the resonator, follow the contour of the latter and facing the resonator are convex at the aperture in the resonator, but which, as they recede from the resonator, rapidly become flatter and thereafter remain flat throughout the remaining distance. Where the reflecting electrode comprises a portion of a sphere as aforesaid, here again the equipotential surfaces adjacent the resonator follow the contour of the resonator and are convex at the aperture but subsequently the equipotential surfaces become flat and then become concave facing the resonator with increasing curvature as they recede from the resonator, the equipotential surface having the maximum curvature being the one closest to the reflecting electrode, the curvature of such surface being the same as the curvature of the reflecting electrode. Since the reflecting electrode is maintained at a negative potential with respect to the potential of the cathode, the zero equipotential surface, i. e., the surface having the

potential of the cathode, is situated between the resonator and the reflecting electrode. Where the reflecting electrode is in the form of a flat disc the equipotential surfaces between the zero equipotential surface and the reflecting electrode are all flat, whilst where the reflecting electrode is of partially spherical form as aforesaid, the equipotential surfaces between the zero equipotential surface and the reflecting electrode are of increasing curvature.

A flat reflecting electrode is satisfactory in that it affords efficient bunching, but where, as is usually the case, the electron beam is divergent as it passes towards the reflecting electrode, very few of the marginal electrons will be reflected back through the aperture in the resonator. Hence the device will lack efficiency.

A system of concave equipotential surfaces as set up by a concave reflecting electrode is efficient in its ability to reflect both the axial and marginal electrons back through the resonator, but is inefficient in that only a small degree of bunching of the electrons occurs.

It will be appreciated therefore that devices embodying either a flat or concave reflecting electrode do not satisfy the aforementioned requirements for efficient operation.

I have found that these requirements can be more completely satisfied compared with known constructions of devices of the kind referred to if the equipotential surfaces which are set up in operation transversely to the path of the electron beam are of concave form facing the resonator, the curvature of said surfaces as they recede from the resonator increasing as they approach the zero equipotential surface and in the region of the central part of the beam decreasing as they recede from the zero equipotential surface.

According therefore to one feature of the invention, an electron discharge device of the kind referred to is provided, in which said reflecting means is so constructed as to be capable, if suitably charged, of setting up equipotential surfaces to cause reflection of the beam, which surfaces transversely to the path of the beam, are of concave form facing the resonator, the curvature of said surfaces as they recede from the resonator increasing as they approach the zero equipotential surface and in the region of the central part of the beam decreasing as they recede from the zero equipotential surface so as to improve the efficiency of the device. As stated above, the equipotential surfaces immediately adjacent the resonator will be convex owing to

the presence of the aperture to the resonator but as the surfaces recede from the resonator the convexity decreases and the surfaces change to concave form. The equipotential surfaces referred to according to the invention are only those surfaces which lie between the point where the surfaces change to concave form and the reflecting means. Also the central part of the beam is, for the purpose of the specification, defined as that part of the beam lying along the centre of the space occupied by the beam and which has a cross-section approximately equal to half the area of the aperture from which the beam emerges from the resonator.

According to another feature of the invention there is provided a circuit arrangement embodying an electron discharge device of the kind referred to in which said reflecting means is so constructed and is maintained at such a potential with respect to the potential of the resonator and cathode of said device as to set up the desired equipotential surfaces referred to above so as to improve the efficiency of the device.

Preferably said reflecting means comprises a reflecting electrode bounded by a short conducting surface which embraces the beam.

The invention may be applied to electron discharge devices employing an electron beam having a substantially circular form in cross-section, in which case the reflecting electrode is of circular form having a peripheral flange and also to electron-discharge devices in which the electron beam is of ribbon-shape in which case the reflecting electrode will be of elongated form to suit the ribbon-shaped beam.

In order that the said invention may be clearly understood and readily carried into effect, it will now be more fully described with reference to the accompanying drawing in which:

Figure 1 illustrates diagrammatically an electron discharge device according to the preferred form of the invention, and

Figure 2 is a diagram on an enlarged scale of the equipotential surfaces which are set up in operation between the resonator and the reflecting electrode of the device, shown in Figure 1. Figure 3 is a section taken along the line 3—3 of Figure 1; Figure 4 is a section taken along a similar line as Figure 3; but showing a modification of the apertures and reflecting electrode.

As shown in Figure 1, a cathode is provided for generating a beam of electrons, the cathode being surrounded by a cathode shield 2. A focussing electrode 3 is provided in the form of an apertured diaphragm which serves, in conjunction with the cathode shield 2, to generate, when the electrodes are maintained at suitable potentials, a focussing field. The hollow resonator is indicated by the reference numeral 4 and is of toroidal shape and provided with a pair of oppositely-disposed apertures 5 and 6 providing a gap through which the electron beam is caused to pass. The field, which serves to reflect the electron beam back through the aperture 6 in the resonator for the purpose of maintaining the generation of oscillations in the resonator, is set up by the provision of a reflecting electrode 7 which, in operation, is suitably charged by maintaining it at a negative potential with respect to the cathode 1.

The device shown in the drawing employs a beam of circular form in cross-section and it is desirable that the electron stream should form a cross-over at the gap. Consequently, the electron beam, when it emerges from the resonator,

will be of divergent form. The reflecting electrode 7, since the electron beam has a circular cross-section, is of circular form and in order to improve the field in the path of the beam so that the requirements aforesaid are more completely satisfied, the electrode 7 is substantially flat and is provided with a short conducting surface embracing the beam, said conducting surface being in the form of a peripheral flange 7a as shown.

Figure 2 of the drawings illustrates some of the equipotential surfaces which are set up between the resonator 4 and the reflecting electrode 7 when the latter is maintained at a negative potential with respect to the cathode 1 and when the resonator 4 is maintained at a positive potential with respect to the cathode 1. As shown, the equipotential surfaces a and b are of convex form in the vicinity of the aperture 6 in the resonator whilst between the equipotential surface b and the surface c shown in the figure the equipotential surfaces change from the convex form to the concave form, as shown. The curvature of the equipotential surfaces as exemplified by the surface d increases as they approach the zero equipotential surface which may be the surface e and said surfaces in the region of the central part of the beam as they recede from the zero equipotential surface decrease in curvature as will be seen from the shape of the surface f. The divergence of the beam in its passage between the resonator 4 and the reflecting electrode 7 may be as indicated by the dotted lines shown in Figure 2 and it will be observed that whilst the decreasing curvature mentioned above holds for the central part of the beam the curvature in the region of the marginal electrons of the beam is greater compared with the curvature of the said surfaces in the region of the central part of the beam. The equipotential surfaces which lie between the surfaces f and the reflecting electrode 7, as exemplified by the surface g further decrease in curvature and those surfaces which lie close to the reflecting electrode will follow the contour of said electrode. The electrons will however be reflected before they reach the reflecting electrode. Thus, by providing the reflecting electrode with a short conducting surface which embraces the beam, a field can be set up between the resonator and the reflecting electrode which is effectively a compromise of the fields which would be produced when using a flat reflecting electrode without a conducting surface embracing the beam and when employing a reflecting electrode of concave form. The equipotential surfaces will of course extend beyond the limits shown in Figure 2 and the portions beyond the limits shown will, where the surfaces are close to the reflecting electrode, tend to lie substantially parallel to the flange 7a. These portions, however, play substantially no part in the reflecting operation since they do not lie in the path of the beam.

It is found that there is an optimum ratio of diameter of the electrode 7 to the width of the flange 7a for maximum efficiency. This optimum ratio is approximately 3, that is to say, the width of the flange 7a is one-third of the diameter of the disc. It is also found that there is an optimum diameter for the reflecting electrode of approximately three to four times the diameter of the aperture 6 in the resonator. The aperture 6, in one example, may be 2 mms., and with such a diameter the diameter of the reflecting electrode is approximately 6 to 8 mms.

The invention can also be applied to electron discharge devices which employ ribbon-shaped beams as aforesaid. In such a case the apertures in the resonator are elongated to accommodate the ribbon-shaped beam and the reflecting electrode is of elongated form suitable for causing reflection of the ribbon-shaped beam. The reflecting electrode in this case will be provided with a short conducting surface embracing the beam, but such surface need not extend around the whole periphery of said electrode but may merely extend along its longer sides. The optimum dimensions referred to above also hold for the elongated form of reflecting electrode, but in this case the ratios referred to are in respect of the minor axes of the reflecting electrode and the elongated aperture.

It is preferred to dispose the reflecting electrode close to the resonator and since, in operation, the resonator will be maintained at a high positive potential and the reflecting electrode at a low or negative potential, there is the danger that, due to the proximity of the reflecting electrode to the resonator, sparking there-between may occur. In order to reduce this possibility the wall of the resonator adjacent the reflecting electrode 7 is provided with an annular depression 8, as shown, in the vicinity of the peripheral flange 1a of the reflecting electrode so that an adequate space is afforded between the periphery of the flange and the adjacent surface of the resonator to reduce the possibility of sparking.

In operation of the device shown in the drawing the focussing electrode 3 may be maintained at a potential of -300 to +300 volts with the cathode 1 and the cathode shield 2 at zero potential, the resonator is at a positive potential of 1000 to 2000 volts and the reflecting electrode 7 at a negative potential of 150 to 500 volts. Figure 3 shows a cross section of Figure 1 taken along the line 3-3 showing an end view of the device utilizing my invention in which a disc electrode arrangement is used. Figure 4 is a view similar to Figure 3, showing a modification utilizing an elongated slot 6c and elongated reflecting electrode 7c having opposed flanges 7c' directed toward the cavity resonator 4.

Figures 3 and 4 show end views of a device utilizing my invention in which Figure 3 shows the disc electrode arrangement 7 and Figure 4 the elongated slot and the elongated reflecting electrode 7c.

I claim:

1. An electron discharge device having a cathode for supplying a stream of electrons, and a reflecting electrode in the path of said electrons, a cavity resonator having a pair of oppositely disposed apertures through which said stream path extends, the transverse dimension of the aperture in said resonator adjacent said reflecting electrode being between one-third and one-fourth the transverse dimension of said reflecting electrode, said reflecting electrode having a conducting flange parallel to the beam path, said

flange having a dimension along the beam path one-third that of the transverse dimension of said reflecting electrode.

2. An electron discharge device having a cathode for supplying a stream of electrons and a reflecting electrode in the path of said electrons, said reflecting electrode comprising a disc, a cavity resonator positioned between said cathode and said reflecting electrode and having oppositely disposed circular apertures in the walls thereof through which the path of said stream of electrons lies, said apertures having a diameter between one-third and one-fourth the diameter of said reflecting electrode, said reflecting electrode having a flange extending toward said resonator and having a dimension along the path of said electrons equal to one-third the diameter of said reflecting electrode.

3. An electron discharge device having a cathode for supplying a stream of electrons, a reflecting electrode in the path of said electrons, a cavity resonator positioned between said cathode and said reflecting electrode, said cavity resonator having oppositely disposed apertures through which the path of the stream of electrons lies, said reflecting electrode being elongated and said apertures being elongated, the shorter transverse axis of the reflecting electrode being between three and four times the shorter transverse axis of said apertures, said reflecting electrode having a flange extending toward said resonator and having a dimension parallel to the path of the electron stream equal to one-third the shorter transverse axis of said reflecting electrode.

4. An electron discharge device having a cathode for supplying a stream of electrons and a reflecting electrode in the path of said electrons, and a cavity resonator positioned between said cathode and said reflecting electrode, and having apertures in the walls thereof through which the electron path lies, said reflecting electrode having a flange extending toward said resonator and lying parallel to the path of the electrons, said resonator and said reflecting electrode being closely spaced, said resonator having a depression registering with the flange on said reflecting electrode.
